United States Patent Office.

ISAAC RANNEY, OF DELAWARE, OHIO.

Letters Patent No. 83,317, dated October 20, 1868.

IMPROVED VARNISH.

The Schedule referred to in these Letters Patent and making part of the same.

To all whom it may concern:

Be it known that I, ISAAC RANNEY, of the city and county of Delaware, and State of Ohio, have invented a new and improved Varnish; and I do hereby declare that the following is a full, clear, and exact description of the same.

This invention has for its object the production of a very lustrous, durable, and economical varnish for general use.

I thoroughly melt two and a quarter pounds of rosin over a fire, raising it to a pretty high heat, after which I set it in a cooler place until reduced to about 250° or 300° Fahrenheit, at which time I add one gallon of benzine or benzole, heated to the boiling-point.

The varnish is then allowed to cool, and is immediately ready for use. It has a fine lustre, is more

durable than the varnishes now in common use, and can be furnished in any quantities desired, and at a mere trifle of expense.

Having thus described my invention,

What I claim as new, and desire to secure by Letters Patent, is—

1. The varnish, compounded substantially as above described.
2. The process herein set forth of making the above-described varnish.

To the above specification of my improvement, I have signed my hand, this 9th day of July, 1868.

ISAAC RANNEY.

Witnesses:

E. S. RANNEY,
J. HIPPLE.
